RAILWAY VEHICLE SPRING

Donald S. Barrows, Rochester, N. Y., assignor to
The Symington-Gould Corporation, Rochester,
N. Y., a corporation of Maryland

Application August 12, 1932, Serial No. 628,609

12 Claims. (Cl. 267—3)

This invention relates to railway vehicles and, more particularly, to the construction and arrangement of the bolster springs and mountings therefor.

5 The principal object of my invention, generally considered, is the provision of a spring nest adapted for handling as a self-contained unit for insertion in the bolster opening of a railway vehicle side frame for the support of an 10 associated bolster.

Another object of my invention is the provision of a practical and economical mounting for spring groups which involve both helical and elliptic or plate springs.

15 Other objects and advantages of the invention relating to the particular arrangement and construction of the various parts will become apparent as the description proceeds.

Referring to the drawings illustrating my invention, the scope whereof is defined by the appended claims:—

Figure 1 is a vertical sectional view on the line 1—1 of Figure 2, looking in the direction of the arrows, and showing a nest of springs embodying my invention.

20 Figure 2 is a plan of the nest of springs shown in Figure 1, partly broken away.

Figure 3 is a sectional view on the line 3—3 of Figure 2, looking in the direction of the arrows.

25 Figure 4 is a fragmentary detail sectional view of the inner edge portion of one of the lower spring plates on the line 3—3 of Figure 2, looking in the direction of the arrows.

30 Figure 5 is a vertical sectional view of another embodiment of my invention on the line 5—5 of Figure 6, looking in the direction of the arrows.

Figure 6 is a fragmentary plan of the nest of 35 springs shown in Figure 5.

Figure 7 is a vertical sectional view on the line 7—7 of Figure 6, looking in the direction of the arrows.

Figure 8 is an exploded view of the spring 40 plates and fastening means therefor shown in perspective and used for mounting the nest of springs shown in Figures 5, 6 and 7.

Figure 9 is a corresponding view of modified forms of two of the spring plates shown in Figure 8.

Figure 10 is a vertical sectional view on the line 10—10 of Figure 11 and showing a modified form of spring nest.

Figure 11 is a plan of the form of spring nest 45 shown in Figure 10.

Figure 12 is an elevational view of the nest shown in Figures 10 and 11, looking in the direction of the long dimension of the elliptic spring.

Figure 13 is a vertical sectional view on the line 13—13 of Figure 14, looking in the direction of the arrows.

Figure 14 is a plan of the modified nest of springs shown in Figure 13, with portions broken away.

Figure 15 is a vertical sectional view on the line 15—15 of Figure 14, looking in the direction of the arrows.

Referring to the drawings in detail, like parts being designated by like reference characters, and first considering the embodiment of my invention illustrated in Figures 1 to 4, inclusive, there is shown a nest of springs 1 involving an elliptic spring or set of elliptic springs 2 and a plurality of helical or coil springs 3 mounted between upper spring plates 4 and lower spring plates 5, and adapted for insertion in the bolster opening of a railway vehicle side frame for the support of the bolster thereof.

As an illustration of the type of side frame for which the present embodiment of my invention is particularly adapted for use with, reference is had to the Kadel and Barrows Reissue Patent No. 18,266, which was reissued under date of November 24, 1931, and particularly Figures 4 and 5 thereof which show the nest of springs mounted in the bolster opening of a double truss side frame or one constructed in accordance with my prior Patent No. 1,652,808 of December 13, 1927 and formed with diagonally extending reinforcing portions 13a.

It will, therefore, be clear that the nest of springs here disclosed may be placed in position in a frame such as shown in Figure 4 of said reissue patent, and with the elliptic spring 2 extending transverse of the frame or longitudinally of the associated bolster, as in said reissue patent.

The elliptic spring 2 of the present embodiment may be considered as comprising a pair of semi-elliptic springs 6 and 7, each of which involves plates 8 held together by spring bands 9 and the extreme ends of each bank of plates resting on end blocks 10, as is usual.

In the present embodiment, the four helical springs 3 are shown as single coil springs, although I do not wish to be limited to this disclosure. Both the upper spring plate 4 and the lower spring plate 5 are substantially H-shaped in plan and each formed of two identical pieces 11 disposed on opposite sides of the elliptic spring 2.

Each piece may be formed flat of the desired shape 45

50

55

The upper spring plate 4 and the lower spring plate 5 are substantially H-shaped in plan and each formed of two identical pieces 11 disposed on opposite sides of the elliptic spring 2.

Each piece may be formed flat of the desired shape 55

and then folded on the center of a rectangular opening which, after folding, provides a wide notch 12 to hold the corresponding spring band 9.

To assemble, the top and bottom half plates 5 are connected together through the two helical springs of the half group, as by means of bolts 13 passing through corresponding apertures 14 in said plates. In order to allow for movement of the upper plates toward the lower upon compression of the springs without buckling the associated bolts, each plate is desirably embossed toward the companion plate, as indicated at 15, so that the bolt used is much shorter than the normal distance between the upper and lower 15 plates, the embossments leaving space to allow for movement of the bolt without buckling upon compression of the springs, as well as providing centering, means or collars for the associated helical springs. In order to provide for interlocking the nest of springs with respect to the side frame and associated bolster, each plate desirably has embossments or nibs 16 adapted to fit in corresponding pockets in the frame, spring plank or bolster and each plate also desirably has 25 a tapering embossment 17 adapting it to nest over the reinforcing corrugation corresponding with that designated by the reference character 13^a of the Reissue Patent No. 18,266 previously referred to. Although, of course, such a corrugation 17 is not needed for cooperation with the bolster, yet in order to make the upper and lower plates interchangeable, said plates are desirably correspondingly formed.

To apply the nest of springs to the frame, the 35 helical springs and their plates may be put in place first and pushed to the side up the double truss incline of the frame. The elliptic spring may then be put in place on the frame, or spring plank if used, and the coil springs and their 40 plates slid down into position. As the notches 12 in the plates embrace the elliptic spring bands, their locating plugs or nibs 16 will enter the corresponding holes or pockets in the frame or spring plank.

45 Referring now to the embodiment of my invention illustrated in Figures 5 to 9, inclusive, a spring nest 1^a is there disclosed involving an elliptic spring 2^a and four double-coil helical springs 3^a, a pair of said helical springs being 50 disposed on each side of the elliptic spring, as in the preceding embodiment. The modified form of spring nest disclosed in these figures is particularly adapted for use with a conventional side frame or one not having the double truss reinforcements 13^a described in connection with the Reissue Patent No. 18,266 previously referred to.

55 In the present embodiment, the free height of the elliptic spring 2^a is greater than that of the helical springs 3^a, and the mounting for the nest 60 of springs comprises four plates of three styles. The lower spring plate 18, generally H-shaped in plan, is formed with a rectangular opening 19 adapted to position the lower spring band 9^a of the elliptic spring 2^a and four spring collars 20 65 adapted to center the inner coils 3^b of the helical springs 3^a. Said lower spring plate is also desirably provided with centering plugs 16^a and curved embossments 15^a apertured at 14^a, as in the preceding embodiment, for receiving the retaining bolts 13^a.

70 The upper spring plate means involves three plates, that is, an individual helical spring plate 21 for each pair of helical springs on a side of the elliptic spring and an elliptic spring plate 22 75 formed with a rectangular aperture 23 receiving

the upper spring band 9^a and side portions 24 which straddle the elliptic spring and terminate in normally horizontal apertured portions 25 which underlie the plates 21 and receive the retaining bolts 13^a thereof. Like the lower plate 18, the upper plate 22 is desirably formed with centering plugs 16^a.

75 In the present embodiment, the nest is desirably assembled in place on the lower spring plate 18, and the upper elliptic spring plate 22 applied, after which the bolts 13^a may be secured in place, as illustrated. The upper helical plates 21 are applied over the end portions 25 of the plate 22, said plates 21, of course, being formed with spring collars 20, embossments 26 to correspond with the embossments of the lower spring plate for a similar purpose, although not necessarily similar in size, and notches 27 to interlock with the centering plugs 16^a of the upper plate 22.

20 The spring plates 21^b and 22^b shown in Figure 9 correspond with the plates 21 and 22 of Figure 8, except that the centering plugs 16^b are formed on the plates 21^b instead of on the plate 22, and the plate 22^b is notched to interlock with 25 said plugs, as indicated at 28. It will also be seen that the embossment 15^b of the plate 21^b corresponds more nearly with the embossment 15^a of the lower plate.

25 It will be understood that when the nest of 30 springs just described is in place in a side frame and serves for support of a bolster so that the elliptic spring 2^a is compressed to a height corresponding with that of the elliptic springs 3^a, the ears 25 of the top retaining plate break contact with the under sides of the helical or spectacle plates 21. Except as specifically described in connection with the present embodiment, the same may correspond with that of the preceding 35 embodiment.

40 Referring now to the embodiment of my invention illustrated in Figures 10, 11 and 12, there is shown a nest of springs 1^c comprising an elliptic spring 2^c and three single coil helical springs 3^c disposed on either side of said elliptic spring, all 45 of said springs being mounted between an upper spring plate 4^c and a lower spring plate 5^c and adapted, like the previous embodiments, for insertion in the bolster opening of a railway vehicle side frame. In the drawings, the elliptic 50 spring is shown compressed until the top plate touches the coil or helical springs 3^c, and for that reason, the connecting bolts 13^c are shown in place with a considerable amount of slack in order to allow for expansion of the elliptic spring 55 to its free height when removed from the side frame.

55 In the present embodiment, the plates 4^c and 60 5^c are generally H-shaped in plan and shown of cast, rather than pressed, construction, as in the preceding embodiments, and centering plugs or collars 15^c are provided sufficiently long so that the helical springs will not slip out when the elliptic spring is free.

65 Provision for compression of the nest of springs without buckling the retaining bolts 13^c is, in the present instance, made by the upstanding embossments 29 which receive the lower ends 70 of said bolts and also function for centering the intermediate helical springs 3^c, said embossments being sufficient in vertical height to not only allow the elliptic spring to expand to its free height, but also to allow full compression of the nest of springs without the lower end of the bolt tending to pass beyond the lower surface of the bottom 75

spring plate 5^c. In the present instance, I have shown the upper spring plate 4^c formed with centering plugs 16^c adapted to engage in corresponding pockets in the associated bolster and the lower plate 5^c may be formed with corresponding plugs, if desired, or the spring supporting portion of the frame, or spring plank if used, may be formed with plugs which center the nest of springs by engaging in the pockets 30 5 provided by the upwardly embossed portions 29 of the lower plate 5^c. Except as specifically described in connection with the present embodiment, the same may be used as the embodiment of Figures 5 to 9, inclusive, and like said previous 10 embodiment, it is especially adapted for use with a conventional frame.

Referring now to the embodiment of my invention illustrated in Figures 13, 14 and 15, there is shown a nest of springs 1^d comprising an elliptic spring 2^d and a pair of single coil helical springs 3^d disposed on either side thereof, and all of said springs mounted between interchangeable pressed metal upper and lower spring plates 4^d and 5^d, respectively which are generally H-shaped in plan.

As in the embodiment of Figures 1 to 4, inclusive, the nest of springs here disclosed is especially adapted for use with a double truss side frame and the spring plates 4^d and 5^d therefor 30 preferably have tapering corrugations 17^d adapted to interlock with the corresponding diagonally extending reinforcing portions of such a frame, as indicated by the reference character 13^a, of Reissue Patent No. 18,266, previously referred to, or corresponding nesting corrugations in an associated spring plank, if used.

For properly centering the springs, each plate 4^d, 5^d desirably has substantially rectangular apertures 12^d preferably defined on two or, if 40 desired, all sides, by flanges 31 which normally extend toward one another and serve to hold the plates and elliptic spring in proper relationship. The flanges 31 which lie adjacent the sides of the bands 9^d which extend transverse to the 45 plates 8^d of the elliptic spring are desirably of a height corresponding with the thickness of the material forming the bands, so that the upper and lower surfaces of the upper and lower plates, respectively, are normally disposed flush with the corresponding surfaces of the bands 9^d, as 50 will be clear from a consideration of Figure 13. For centering the helical springs 3^d, the usual collars 15^d are desirably provided. As in the first embodiment, the spring plates are desirably 55 properly centered with respect to the bolster and associated side frame or spring plank, if used, by plugs 16^d which, in the present embodiment, are pressed therefrom as in the embodiment of Figures 1 to 4, inclusive.

In the present embodiment, the nest of springs may either be handled as a unit and inserted in place in the bolster opening of a side frame, or it may be built up in said bolster opening by first applying the lower spring plate 5^d, then inserting the springs in place thereon, and finally applying the upper spring plate 4^d. The positioning of the nest of springs of the present embodiment in the bolster opening of a side frame 70 will correspond with that of the first embodiment. It will also be understood that although the nest of springs disclosed is particularly adapted for use with a double truss side frame, it may also be used with a conventional frame when the 75 corrugations 17^d do not function for interlocking

the nest in place, such interlock being provided by the plugs 16^d.

From the foregoing disclosure, taken in connection with the accompanying drawings, it will be seen that I have devised various forms of 5 spring nests adapted for handling as self-contained units for insertion in or removal from the bolster opening of a railway vehicle side frame, said units involving mounting plates which are particularly adapted for properly spacing a combination of springs involving both helical and elliptical or plate springs. It will also be seen that the free height of the elliptic spring may correspond with or be different from that of the associated helical springs.

Although preferred embodiments of my invention have been disclosed, it will be understood that modifications may be made within the spirit and scope of the appended claims.

I claim:—

1. A spring nest, adapted for handling as a self-contained unit for insertion in the bolster opening of a railway vehicle side frame for the support of a bolster, comprising upper and lower spring plates formed to respectively interlock 25 with an associated bolster and frame, and with both helical and elliptic springs therebetween, said plates, for that purpose, having portions extending toward one another around the bands of said elliptic spring for holding it in place. 30

2. A spring nest adapted for insertion in the bolster opening of a railway vehicle side frame and comprising an elliptic spring and helical springs disposed on either side thereof, said helical springs on either side of said elliptic spring 35 having individual upper and lower spring plates, the adjacent edges of the upper spring plates and those of the lower spring plates being notched to interlock with the spring bands of said elliptic springs, and normally vertical bolts connecting 40 the upper and lower spring plates on either side of said elliptic springs.

3. A spring nest comprising a lower spring plate, helical and elliptic springs seated thereon, said elliptic spring being disposed between said 45 helical springs, said elliptic spring having a free height greater than the helical springs and provided with an individual upper plate, and individual upper helical spring plates lying on either side of said elliptic spring plate normally engaging 50 the upper surfaces of downwardly offset portions thereof and connected to the lower spring plate.

4. A spring nest comprising a lower spring plate, an elliptic spring and helical springs disposed on opposite sides thereof seated on said plate, an individual upper spring plate interlocking with said elliptic spring, and individual spring plates lying on either side of said elliptic spring and seated on the helical springs, said upper elliptic spring plate having ears normally underlying the upper helical spring plates, said ears, registering portions of said upper helical spring plates, and the registering portions of the lower plate being apertured, and connecting bolts disposed 60 in said apertures. 65

5. A spring nest comprising interchangeable upper and lower pressed metal spring plates, an elliptic spring with a plurality of helical springs disposed on either side thereof and all lying between said spring plates, said plates having rectangular apertures receiving corresponding portions of the bands of said elliptic spring, a pair of sides of the aperture in each plate being defined by flanges extending toward the other plate and 75

of a depth corresponding with the thickness of material of the spring band so that the outer surfaces of the plates normally lie flush with the corresponding surfaces of the spring bands when the parts are assembled.

6. A spring nest comprising spaced upper and lower spring caps, helical springs and an elliptic spring interposed between said caps, one of said caps being formed of counterpart plates each 10 of which comprises a flat sheet provided with a rectangular opening, and an edge thereof folded to bisect said opening, thereby forming a notch for engaging the spring band of the elliptic spring.

7. A spring nest comprising a lower spring 15 plate, helical and elliptic springs seated thereon, said elliptic spring provided with an individual upper plate having portions thereof extending outwardly of the elliptic spring and individual upper helical spring plates superimposed 20 on the outwardly extending portions of said elliptic spring plate and connected to the lower spring plate.

8. A spring nest comprising upper and lower spring plates generally H-shaped in plan, helical and elliptic springs disposed between said plates, said elliptic spring being interposed between the helical springs and having the longitudinal axis thereof extending parallel to a plane passing through the centers of some of the helical springs, 30 said plates being provided with positioning means formed on the cross piece of said H adapted to engage the spring band of the elliptic spring and a plurality of embossments and collars formed on said plates extending within said helical springs, and means extending through said embossments connecting said plates.

9. In a spring assembly comprising upper and lower spring caps, helical springs, and an elliptic spring disposed between said caps, the upper of said caps being H-shaped in plan and provided with formations thereon for centering the helical 5 springs and for engaging a top spring band of the elliptic spring, and a lower spring band of the elliptic spring having a bearing surface coplanar with an outer bearing surface of the lower spring cap.

10. A spring nest comprising spaced upper and lower spring caps, helical springs, and an elliptic spring interposed between said caps, one of said caps being formed of a plate comprising a flat sheet provided with a rectangular opening, and 15 opposing edges thereof folded to bisect said opening, thereby forming notches for engaging a spring band of the elliptic spring, said folded portions bearing against a leaf of said elliptic spring.

11. A spring cap comprising oppositely disposed 20 spring plates, each having a rectangular opening adapted to receive the spring band of an elliptic spring, the adjacent edges of said plates being folded to bisect said opening, and projections on the outer surfaces of said plates for locking said 25 spring cap in position in a bolster opening.

12. A spring cap for a group of helical and elliptic springs comprising a plurality of helical and elliptic spring plates, the elliptic spring plate having a rectangular opening therein the edges 30 of which interlock with a spring band of the elliptic spring, said elliptic spring plate having extensions at opposed ends thereof normally engaging the helical spring plates.

DONALD S. BARROWS.
